UNITED STATES PATENT OFFICE.

ADAM MIEDEN, OF RENO, NEVADA.

CLIP.

1,204,373.

Specification of Letters Patent. Patented Nov. 7, 1916.

Application filed June 5, 1915. Serial No. 32,434.

To all whom it may concern:

Be it known that I, ADAM MIEDEN, a citizen of the United States, residing at Reno, in the county of Washoe and State of 5 Nevada, have invented a new and useful Clip, of which the following is a specification.

This invention relates to an improvement in clips which may be applied to books so 10 that the book can be attached to the pocket, or it for retaining the book in the pocket, or it may be used for fastening papers and fabrics together, and as a clothes-pin.

The invention consists of certain novel 15 features of construction and combinations of parts, which will be hereinafter described and pointed out in the claims.

It will be evident that many slight changes may be made in the form and arrangement of the several parts to be described without departing from the spirit and scope of the invention, and hence I do not wish to be limited to the exact construction as herein set forth.

25 In the accompanying drawing, Figure 1 is a view in elevation showing the invention applied to the cover of the book. Fig. 2 is an enlarged vertical sectional view through the clip and book. Fig. 3 is a view 30 in rear elevation showing the application of the clip to a book cover. Fig. 4 is a top plan view of the clip, taken on the line 4—4 of Fig. 2, showing its application to the cover. Figs. 5 and 6 are front and rear 35 elevations showing the clip applied to a pad for holding loose papers or other articles. Fig. 7 is a top plan view. Fig. 8 is a longitudinal vertical sectional view of application of the device shown in Figs. 5 and 6. 40 Fig. 9 is a sectional view on the line 9—9 of Fig. 6. Fig. 10 is a view in front elevation of the clip detached, and Fig. 11 is a view in side elevation.

The clip is preferably made from a single 45 length of wire returned upon itself to provide a pair of strands which are bent to form front and rear members and a bridge joining the upper ends of the members. The front member comprises the parallel 50 strands 1 which are preferably in contact. The lower terminal of the front member is

closed. This lower terminal is bent upwardly and inwardly against the rear face of the front member to provide laterally extending eyes or loops 2, joined by a cross 55 bar resting against the rear faces of the strands 1. The upper end of the front member has its strands bent rearwardly at right angles to the front member to provide a bridge 3. At the rear end of the bridge 60 3 the strands diverge laterally and oppositely and form a transversely extending shoulder 4. From the opposite ends of the shoulder 4, the strands extend downwardly and preferably converge to form the rear 65 member. The rear member is composed of two strands 5, which are slightly concaved longitudinally, and the lower terminals of the strands are brought together, that is, the strands extend or converge inwardly 70 from their upper ends. The concaving, or bowing inwardly, of the strands 5 of the rear member toward the front member, as shown in Figs. 2, 8 and 11, serves to hold the rear member yieldingly in contact with 75 material placed between the members throughout the entire lengths of the strands 5, as shown in Fig. 2, and throughout substantially their entire lengths as shown in Fig. 8. It is thus seen that in the use of 80 this clip, the material is pressed against the front member, and is held between the members 1 and 5, throughout a considerable extent depending upon the thickness of the material in the clip. The clip thus exerts 85 a firm binding action upon the material proportionally to the thickness of the material, the binding action being not at a single biting point, but taking effect throughout a long line of consecutively engaging points, 90 the thicker the material placed in the clip, the greater will be the pressure on the strands 5 to straighten the same, and the greater will be the pressure of the bowed strands against the material, as the thicker 95 the material the greater is the engaging lengths of the bowed strands. By this peculiar construction, a clip is provided which automatically adjusts itself and its binding action to the thicknesses of materials placed between the members of the clip. The lower ends of the strands 5 ex- 100

tend or flare outwardly, as at 6. The cross bar or transverse portion 7, of the terminal of the front member, rests upon or engages the strands 5 of the rear member, forming 5 a tight closure between the two members.

In Figs. 1, 2, 3 and 4, the clip is shown as applied to the cover of a book. The strands 5 are inserted through openings 8 in the cover 9 and extend parallel with the inner 10 surface of the cover. Bearing plates or straps 10 are inserted through the cover from the exterior, and the ends are bent against the inner surface of the cover, the flaring ends 6 of the clip resting or bearing 15 against the plates.

The shoulder 4 engages across the outer face of the cover 9 and holds the bridge portion 3 away from the cover in an outwardly projecting position. It also holds 20 the rear member flat against the inner side of the cover 9 and keeps the strands 5 from sliding downwardly against the inner side of the cover.

Applied to the inner side of the cover is a 25 lining 11 of paper for maintaining the rear member or strands 5 against the cover portion 9. These bearing plates 10 prevent lateral movement of the clip and assist in preventing the terminals of the strands 5 from 30 being forced through the cover 9, especially when the cover is made of some light material.

When the terminal of the front member is raised, considerable pressure or strain is 35 placed against the ends 6 of the strands 5 of the rear member, and the strands 5 are caused to bow, increasing the concavity of the strands, thereby producing a tension upon the front member which insures its 40 return into engagement with the rear member, for confining the papers or articles between the two members.

In the application of the clip, as shown in 45 Figs. 5, 6, 7, 8 and 9, the terminals of the strands 5 are connected together by a strap or fastener 12, which encircles the rear member and passes through a pad or board 13, and the terminals 14 of the strap or fastener are bent against the opposite side of the pad. 50 The clips can be fastened to the book covers or pads in any suitable manner, but I have shown them connected to the cover and pad by means of fastening means 10 and 12.

It will be seen from the foregoing that I 55 have provided an article of manufacture which can be made and sold at a small cost, and which is simple and positive in its operation.

The tension which is created between the 60 front and rear members upon the raising of the front member from engagement with the rear member, insures the return of the front member into engagement with the rear member for confining the smallest or thinnest article therebetween. The space formed 65

between the upper terminals of the front and rear members is sufficient to permit of the easy application of the clip to a pocket of a garment, or over a pad, or to a clothes-line without straining the clip.

Another feature of this invention is in the peculiar construction of the lower terminal of the front member. The bending of the transverse portion or lower end 7 of the front member rearwardly, so that it engages the rear surfaces of the strands 1, produces the eyes 2, thereby forming an enlarged terminal, which affords greater strength to the terminal of the front member, and when the enlarged terminal is 70 brought into engagement with the strands of the rear member a greater bearing surface is provided for confining papers and articles therebetween. With an enlarged terminal of this character there is no danger of the 75 terminal becoming weakened, due to the constant raising of the front member by the terminal, and thereby losing its resiliency and gripping power.

What is claimed is,—

1. A clip comprising a front member, a rear member, and a bridge joining the upper ends of the members, said members and bridge comprising a single length of wire returned upon itself to provide the front 95 member having a pair of strands, said strands being rolled laterally and oppositely from the lower end of the front member to provide lateral loops thereat which are joined across the inner face of the front 100 member, the strands being turned inwardly at right angles from the top of the front member to provide the bridge, and being diverged laterally and oppositely from the rear end of the bridge to provide a trans- 105 verse shoulder across the top of the rear member, the strands of the rear member extending downwardly from the opposite ends of said shoulder.

2. A clip comprising a front member, a 110 rear member, a bridge joining the upper ends of said members, said members and bridge comprising a single length of wire returned upon itself to provide the front member having a pair of strands, the strands of 115 the front member extending in contact throughout substantially the length of the front member and being rolled laterally and oppositely from the lower end of the front member to provide loops at the opposite 120 sides thereof which are joined across the inner face of the front member, the strands at the upper end of the front member being turned inwardly at right angles to provide the bridge, and being diverged laterally and 125 oppositely from the rear end of the bridge to provide a transverse shoulder across the top of the rear member, the strands of the rear member converging downwardly from the opposite ends of said shoulder to a point 130

below the lower end of the front member and then being bent laterally and oppositely from said point, said rear member being bowed toward the front member, and means
5 engaging the lower ends of said converging strands to secure the same from spreading and to hold the rear member in place.

In testimony that I claim the foregoing as my own, I have hereto affixed my signature in the presence of two witnesses.

ADAM MIEDEN.
